UNITED STATES PATENT OFFICE.

JOSEPH FOSSA, OF DANVERS, MASSACHUSETTS, ASSIGNOR TO UNITED SHOE MANUFACTURING CORPORATION, OF PATERSON, NEW JERSEY, A CORPORATION OF NEW JERSEY.

SEWING MACHINE.

Application filed January 11, 1919. Serial No. 270,736.

To all whom it may concern:

Be it known that I, JOSEPH FOSSA, a citizen of the United States, residing at Danvers, in the county of Essex and State of Massachusetts, have invented certain new and useful Improvements in Sewing Machines; and I do hereby declare the following to be a full, clear, and exact description of the invention, such as will enable others skilled in the art to which it appertains to make and use the same.

The invention relates to overseam sewing machines, and more particularly to the mechanism for laying a stay cord within the seam on the under side of the work.

The invention is designed primarily for use in machines for sewing overseams about eye-ended buttonholes, although applicable to other overseam machines. The throat plate of a buttonhole sewing machine of the above type is usually provided with a guide through which a stay cord is directed into the range of action of the stitch forming mechanism so that during the sewing the cord is laid within the seam on the under side of the work. In sewing a series of spaced buttonholes the stay cord usually leads from one hole to another, or is severed and held with the under thread between successive buttonhole sewing operations. In either case there is an undesirable waste of cord which may add materially to the cost of production.

The mechanism of the present invention avoids unnecessary waste of cord by cutting from the cord supply a length of cord substantially the length of the seam to be sewed and laying it within the seam on the under side of the work. The cutter which cuts the length of cord from the cord supply is preferably located back of the guide in the throat plate through which the cord leads to the seam, and is preferably actuated to sever the cord at such a point during the sewing that the end of the piece severed from the cord will substantially register with the end of the finished seam. After the cord is severed, and before or at the beginning of the next sewing operation, the end of the cord supply is projected through the guide in the throat plate, so that the cord will be laid in the succeeding seam.

A mechanism embodying the preferred form of the invention is shown in the drawings, in which Figure 1 is a transverse sec-

tional elevation on line 1—1, Fig. 2, showing so much of a buttonhole sewing machine as is necessary to illustrate the application of the present invention thereto; Fig. 2 is a plan view, with the work supporting plates removed, and the parts of the under sewing mechanism which is carried by the turret omitted; Fig. 3 is a similar view showing the parts in a different position; Figs. 4 and 5 are detail plan views showing the cord feeding segment in different positions; and Fig. 6 is a detail perspective view of the cord guiding and cutting block.

In the drawings the invention is shown embodied in a buttonhole sewing machine having the general construction and mode of operation of the machine shown and described in Patent No. 1,063,880, June 3, 1913. The stitch forming mechanism of this machine comprises an upper needle 2, an under needle 4 and a looper 6 which cooperate in sewing an overseam. The upper needle is mounted in a rotary support, and the under needle and looper are mounted in a rotary turret 8 which also carries the throat plate 10. The work is carried in a clamp, the work supporting plates of which are indicated at 12, and the work clamp is fed and the supports for the upper and under thread mechanism are rotated during the sewing to form an overseam about an eye-ended buttonhole, as fully described in the above patent.

The mechanism for severing a length of stay cord from the cord supply, and laying it within the seam on the under side of the work, comprises a cord guide 14 formed in the throat plate, and cord severing and feeding mechanism arranged back of the guide and operating to sever from the cord supply a length of cord substantially equal to the length of the seam, and to project the end of the cord supply through the guide in the throat plate and into the range of action of the stitch forming mechanism. As shown, this mechanism comprises a cord guiding and cutter block 16 secured in an inclined position upon the bracket 18 in which the throat plate is secured. The block is provided at its rear end with a guiding lug 20 and a guideway 22 arranged in alignment with the guide 14 in the throat plate. The stay cord leads through a guide 24 on the turret, around the guide lug 20, and through the guideway 22 to the throat plate.

The block 16 is provided with a rib 26 arranged at one side of the mouth of the guideway 22, the upper edge of which cooperates with a cutter blade 28 in severing 5 the cord between the mouth of the guideway and the throat plate. The cutter blade is secured on one arm of a cutter lever 30, which is mounted on a stud 32 and is provided with a second arm arranged to be 10 engaged by a cam 34 on the turret bracket. The cutter lever is held yieldingly in retracted position by a spring 36 coiled about the stud, and its position is determined by a stop pin 38 which passes through a slot in 15 the lever. At a predetermined point during the sewing of a buttonhole the rotation of the turret carries the cutter lever against the cam 34, so that the cutter is operated to sever the cord back of the guide in the 20 throat plate. The parts are so located that the end of the piece of cord severed from the cord supply will substantially register with the end of the seam at the completion of the buttonhole.

25 The mechanism for feeding forward the end of the supply cord, and projecting it through the guide in the throat plate into the range of action of the stitch forming mechanism, so that it will be properly laid 30 within the next succeeding seam, comprises a cord feeding segment 40 provided with teeth on its periphery against which the cord is pressed by a spring presser plate 42. The feeding segment is pivoted at one 35 side of the block 16, and its hub is provided with a gear segment 44 engaged by the teeth of a segment 46 which is mounted on a stud 48 on the turret. The segment 46 is held in its advanced position indicated 40 in Fig. 5 by a spring 50 coiled about the stud 48 and connected with the hub of the gear segment 46. The segment 46 is provided with an arm 52 which projects into 45 position to be engaged by a cam 54 on the turret bracket. During the final rotation of the turret, as a buttonhole is completed, the arm 52 rides up the cam 54, so that the feeding segment is retracted into the position indicated in Fig. 4. As the turret 50 starts to rotate at the beginning of the next sewing operation, and before the initial stitch of the seam is formed on the under side of the work, the arm 52 rides off the cam 54, so that the feeding segment is 55 quickly advanced into the position indicated in Fig. 5, thus feeding the cord forward and projecting its end through the guide 14 in the throat plate so that it will be covered and attached to the under side 60 of the work by the initial stitches of the overseam. The cord will now be laid in the seam on the underside of the work in the usual manner, the feed of the work drawing the cord through the guide in the throat 65 plate and from the cord supply until the

cutter is again operated to sever the cord as above described.

A length of cord substantially equal in length to the length of the seam extending about the buttonhole, is thus automatically 70 severed from the cord supply and laid in the seam on the underside of the work during each buttonhole sewing operation, and unnecessary waste of stay cord is avoided. By proper adjustment or arrangement of the parts the ends of the cord 75 may be caused to extend more or less beyond the ends of the seam, or to be completely covered thereby.

While it is preferred to employ the specific construction and arrangement of parts shown and described in embodying the invention in a machine of the patent above referred to, it will be understood that this construction and arrangement is not essential to the broader features of the invention, and may be varied or modified as found desirable or best suited to the construction and arrangement of parts in the machine in which it is to be embodied.

What is claimed is:—

1. A sewing machine, having, in combination, stitch forming mechanism for sewing an overseam, a throat plate below the work provided with a stay cord guide, 95 means for cutting the cord back of the guide, and means for projecting the end of the supply cord through the guide.

2. A sewing machine, having, in combination, stitch forming mechanism for 100 sewing an overseam, a throat plate below the work provided with a stay cord guide, a cord cutter, automatically acting mechanism for actuating the cutter during the sewing to sever a length of cord substantially equal to that of the overseam, and automatically acting means for projecting the end of the supply cord through the guide in the throat plate.

3. A sewing machine, having, in combination, stitch forming mechanism for sewing an overseam including upper and under thread mechanism, a turret below the work carrying the under thread mechanism, a stay cord guide on the turret, a cord cutter 115 back of the guide, and cord feeding means for projecting the end of the supply cord through the guide.

4. A sewing machine, having, in combination, rotary stitch forming mechanism 120 for sewing an overseam including a rotary support, means on the support for laying a stay cord within the seam, and a cord cutter on the support operated by the rotation of the support during the sewing.

5. A sewing machine, having, in combination, rotary stitch forming mechanism for sewing an overseam including a rotary support, means on the support for laying a stay cord within the seam, a cord cutter 130

on the support operated by the rotation of the support during the sewing, and a cord feeder on the support operated by the rotation of the support. 50

5. 6. A sewing machine, having, in combination, stitch forming mechanism for sewing an overseam, a rotary support for the stitch forming mechanism, means rotating with the support for laying the stay cord within the seam, means rotating with the support for severing a length of cord substantially equal to that of the overseam, and means rotating with the support for advancing the end of the cord supply into the range of action of the stitch forming mechanism. 15

7. A sewing machine, having, in combination, stitch forming mechanism for sewing an overseam, a rotary support for the stitch forming mechanism, a cord guide on the support for laying a stay cord within the seam, means on the support for severing the cord back of the guide, and means on the support for projecting the cord end through the guide into the range of action of the stitch forming mechanism. 20

8. A sewing machine, having, in combination, rotary stitch forming mechanism for sewing an overseam, including a rotary support, means on the support for laying a stay cord within the seam, and a cord cutter on the support. 30

9. A sewing machine, having, in combination, rotary stitch forming mechanism, mechanism for sewing an overseam, including a rotary support, a stay cord guide on the support, a cord cutter on the support, and cord feeding means on the support for projecting the end of the cord through the guide. 35

10. A sewing machine having, in combination, stitch forming mechanism for sewing an overseam, a throat plate below the work, means for laying a stay cord within the seam on the same side as the throat plate, automatically acting means for severing a length of cord substantially equal to that of the

overseam and automatically acting means for advancing the free end of the cord supply into the range of action of the stitch forming mechanism. 55

11. A sewing machine having, in combination, stitch forming mechanism for sewing an overseam, a throat plate below the work, a cord guide on the same side of the work as the throat plate for laying a stay cord against the work within the seam, means for severing the cord back of the guide, and means for projecting the cord end through the guide into the range of action of the stitch forming mechanism. 60

12. A sewing machine having, in combination, stitch forming mechanism for sewing an overseam, a throat plate below the work, means for laying a stay cord within the seam on the same side of the work as the throat plate, automatically acting means for severing the cord during the sewing, and automatically acting means for advancing the end of the cord supply into the range of action of the stitch forming mechanism. 65

13. A sewing machine having, in combination, stitch forming and work feeding mechanism for sewing an overseam about a buttonhole, a throat plate below the work, and mechanism for severing from a cord supply prior to the completion of the seam a length of stay cord substantially the length of the overseam and for laying it within the seam on the same side of the work as the throat plate. 70

14. A sewing machine having, in combination, stitch forming and work feeding mechanism for sewing a pre-determined length of overseam, a throat plate below the work, and automatically acting mechanism for severing from a cord supply prior to the completion of the seam a length of stay cord substantially the length of the overseam, and for laying it within the seam on the same side of the work as the throat plate. 75

JOSEPH FOSSA.
